J. M. JONES.
DOUBLE ACTING PUMP.
APPLICATION FILED JUNE 30, 1915.

1,208,977.

Patented Dec. 19, 1916.

UNITED STATES PATENT OFFICE.

JOHN MASON JONES, OF PEORIA, ILLINOIS.

DOUBLE-ACTING PUMP.

1,208,977.

Specification of Letters Patent. Patented Dec. 19, 1916.

Application filed June 30, 1915. Serial No. 37,185.

To all whom it may concern:

Be it known that I, JOHN MASON JONES, a citizen of the United States, and a resident of Peoria, in the county of Peoria and State 5 of Illinois, have invented certain new and useful Improvements in Double-Acting Pumps, of which the following is a full, clear, and exact description, reference being had to the accompanying drawing, forming 10 part of this specification.

My invention relates to double acting pumps adapted more particularly for service in drilled wells though it is capable of use in any place where it is desired to pump 15 water with the least possible expense of power and the minimum of repairs.

The object of my invention is to provide a pump which is economical in service, inexpensive to build and maintain, reliable in 20 action and which, should occasion require, can be easily and quickly removed from the well for inspection or repairs and then easily restored to working position.

The novelty of my invention will be hereinafter more fully set forth and specifically pointed out in the claims.

In the accompanying drawing, Figure 1 is a vertical sectional elevation of a pump embodying my invention and showing all 30 of the working parts thereof. Fig. 2 is a plan section of the upper discharge valve cage and associated parts, taken on the dotted line A—A of Fig. 1. Fig. 3 is a sectional plan view taken on the dotted line 35 B—B of Fig. 1. Fig. 4 is a plan view of the seat of the lower suction valve and also the foot valve to be referred to later. Fig. 5, is a vertical view partly in section, showing the lower end of the pump cylinder, the suction pipe with its foot valve and the well 40 casing.

The same numerals of reference are used to indicate identical parts in all the figures.

Referring more particularly to Figs. 1 and 5, 1 represents the usual or any suitable 45 well casing which is driven into the ground and forms the well proper. Inserted within this casing and suitably supported from the top of the well, is the delivery pipe 2, to the lower end of which is screwed the seat ring 3, and to the latter is suitably screwed the suction pipe 4 which extends downward and well under the level of the water in the well. The lower end of the suction pipe 4 50 is provided with a suitable foot valve which consists of the seat 5, disk 6, spring 7 and

stud 8, these latter parts being shown in Fig. 5.

As shown in Fig. 1, the seat ring 3 is provided with an inner tapered seat 9, within 60 which the ported plug or casting 10 is accurately fitted, and to the lower end of this plug 10 is screwed the pump cylinder 11, which is preferably composed of brass tubing and is of a length sufficient for the reception of the interior parts of the pump and also the stroke of such parts. The lower end of the pump cylinder is closed by the lower suction valve 12 which is in all respects, except as to size, similar to the foot 70 valve before described. A series of upper suction ports 13 extend from the space between the pump cylinder 11 and the suction pipe 4, these ports being located in the lower part of the plug 10 as shown clearly in Fig. 75 1. The upper suction valve 14, held in place against its seat covering the ports 13 by spring 15, which in turn is held in position by ring 16 screwed into the lower end of plug 10, serves to close the ports 13, this 80 valve being in the form of a ring with a comparatively large center opening as shown.

A second series of ports 17 extend upward through the plug 10 as shown in Fig. 1, and these ports are normally closed by the lower 85 discharge valve 18 which is held in place against its seat by the spring 19 which bears against the lower part of the gland 20.

The gland 20 has a lower flange 21 which affords a stop to limit the upward movement 90 of the valve 18 and the upper end of this gland is provided with the packing 22 which forms a water-tight joint against the outside of the hollow piston rod 23. To the lower end of the piston rod 23 is suitably attached the piston 24, which is provided with the cup leathers 24' and followers 24'', two of the cup leathers being turned downward and the other two upward in such manner that the piston will suck and deliver water 95 when operated in either direction.

The piston 24 is attached to the lower end of the piston rod 23 by means of the connector 25 which serves the purpose of connection between these parts and also to compress the followers and cup leathers to hold the same in proper position.

The piston has a central water passage as shown and this passage connects with the interior of the hollow piston rod, 23, which 110 latter extends upward and is suitably attached to the lower ring or valve seat of the

upper discharge valve 26, the lower ring or seat 27 of which, in addition to the connection to the piston rod, is screwed to the cage 28 which in turn has its upper portion 5 screwed over the lower end of the operating rod 29 in such manner that when this rod is reciprocated, it, through the connections and parts described, reciprocates the piston to pump water from the well.

10 The operation of the various parts of the pump is as follows, the parts being shown at or near the end of the up stroke of the piston, and all of the ports, cavities and passages are assumed to be full of water. On 15 the down stroke of the piston the water within the lower part of the cylinder is forced up through the hollow piston rod, through the upper discharge valve and into the delivery pipe, while at the same time a 20 partial vacuum is produced above the piston which draws water into the upper part of the cylinder through the ports 13, past upper suction valve and into the upper part of the pump cylinder, this water being 25 drawn from the space between the cylinder and the suction pipe. At the completion of the down stroke of the piston the upper suction and upper discharge valves both close and upon the beginning of the up stroke the 30 water which has just been drawn into the upper part of the cylinder is forced through the discharge ports 17 and past the lower discharge valve and into the delivery pipe, while at the same time water is drawn into 35 the lower part of the cylinder through the lower suction valve, which up stroke when completed or nearly so will bring the parts to the positions shown and thus complete a cycle of operation.

40 It is to be observed that there are no ports, openings or passages or other means of communication between the suction and delivery pipes and that there is, consequently, no possibility of leakage between 45 the suction and delivery pipes, and that in consequence of this construction it is possible to maintain the water properly within the pump and that it will not be necessary to prime a pump of this construction even 50 when the cylinder is placed a considerable distance above the level of the water in the well.

It is also to be noted that I employ a single foot valve of the flat seated type and 55 that this valve is always submerged, thus providing against the loss of the water in the suction pipe.

It is to be further observed that I can entirely remove from the well all of the pump 60 mechanism without in any way interfering with the water tightness of the stand pipes above the foot valve and that the removal of these parts includes the cylinder and all of its parts, including all of the suction and 65 all of the discharge valves. To make such

a removal, the operating rod is pulled upward until the piston comes against the lower end of the plug 10 whereupon a further movement of the operating rod lifts the said plug and with it, all of its associated and connected parts as will be readily understood.

Again, it is to be observed that all of the water ports and passages are of liberal size and that there are no tortuous passages for 75 the water, and that the water in passing through this pump, can do so with the least possible amount of friction, and still further that the construction and arrangement of the parts is such that I can use a cylinder in a given size of well, far in excess of the size cylinder which it has hitherto been possible to use, consequently enabling my pump to deliver a larger amount of water 80 than pumps which have been built here- 85 before.

If desired, the lower edge of the seat of the lower suction valve 12 may be provided with guides 30 extending radially therefrom and bearing against the inside of the suction 90 pipe so as to maintain the cylinder in a central position in the suction pipe.

Having thus fully described my invention, I claim;

1. In a double acting pump, the combination of a seat ring connecting a suction and delivery pipe, a suction pipe extending below said seat ring, a delivery pipe supporting said seat ring, a ported plug seated within said ring and removable therefrom, 100 suction and discharge valves seated within and on said plug, a cylinder attached to the lower part of said plug and located within said suction pipe, centering device on the lower portion of said cylinder for maintaining the latter in proper position within said suction pipe, a piston within said cylinder, means for operating said piston, a suction valve within the lower end of said cylinder, a discharge valve carried by said 110 piston operating means, and a foot valve within the lower end of said suction pipe.

2. In a deep well pump the combination of a delivery pipe, a suction pipe connected thereto and extending below the surface of the water in a well, a foot-valve near the lower end of said suction pipe, a pump cylinder and associated parts located above said foot-valve, and means for removing said pump cylinder and associated parts from the well without disturbing said foot-valve or lowering the level of the water in said suction pipe beyond an amount equal to the displacement of the parts removed.

3. In a deep well pump the combination of a stand pipe extending below the surface of the water in a well, a divisional connection in said stand pipe which converts the lower part thereof into a suction pipe, a foot-valve in the lower part of said suction 130

pipe, a pump cylinder and associated parts normally mounted by and at said divisional connection, and means for removing said cylinder and associated parts from the well 5 without materially changing the level of the water in said stand pipe.

4. In a deep well pump the combination of a stand pipe extending below the surface of the water in a well, a pump-cylinder- 10 supporting divisional connection in said stand pipe which converts the lower part thereof into a suction pipe, a foot-valve in

the lower part of said suction pipe, a pump cylinder with a head portion seating in and supported by said pump-cylinder-supporting divisional connection, suction and discharge valves for said pump cylinder, a piston within said cylinder, means for operating said piston, and means for removing said cylinder and piston and said suction and discharge valves from the well without releasing the water in said stand pipe. 15

JOHN MASON JONES.
